UNITED STATES PATENT OFFICE.

LEO J. KAHLO AND ROY B. CAMERON, OF DEFIANCE, OHIO.

LAMP.

1,083,214.

Specification of Letters Patent. Patented Dec. 30, 1913.

Application filed June 13, 1913. Serial No. 773,399.

To all whom it may concern:

Be it known that we, LEO J. KAHLO and ROY B. CAMERON, citizens of the United States, of Defiance, in the county of Defiance, in the State of Ohio, have invented new and useful Improvements in Lamps, of which the following, taken in connection with the accompanying drawings, is a full, clear, and exact description.

10 This invention relates to certain improvements in lamps, and pertains more particularly to vapor lamps in which a liquid under pressure is vaporized, mingled with air and supplied to an incandescent mantle.

15 It is well known among those familiar with the art that vapor lamps heretofore produced have had a form peculiar to themselves and their operation which distinguished them from lighting means adapted

20 to be operated in a different manner, particularly electric means, and that there have been and are many desirable forms of lighting fixtures, to which form vapor lamps are not adapted.

25 The object, therefore, of our invention is to provide a lamp of simple construction and a minimum number of parts so formed and arranged that the distinguishing and necessary features of this style of lamp—that is the vaporizing tube and the mixing chamber, shall be readily inclosed in an ordinary shade and normally out of sight, so that the appearance of almost any electrical fixture may be duplicated.

30 Another object is to provide a removable vaporizer extending substantially parallel with and adjacent to the support for the lamp so as to utilize a minimum of space, and having a portion lying adjacent the mantle of the burner so as to be heated by radiation therefrom, whereby the gasolene or similar liquid fuel will be automatically and efficiently vaporized after the lamp is once lighted.

35 A further object is to provide means for removably supporting the lower end of the vaporizing tube and means for readily cleansing the discharge orifice in the vaporizing tube without removing the tube from its supports.

Other objects and uses will appear from the following description.

In the drawings Figure 1 is a cross sectional view of our lamp. Fig. 2 is a perspective view of the vaporizing tube apart from the lamp.

In order that our invention may be clearly understood, we have shown it as supported by a drop tubing —1— of any desired length, extending, as shown, from the ceiling of a room, but it is apparent that it may, with equal efficiency, extend from and be supported by any other portion of the wall of a building, as particularly the side wall. A portion of the lower end of the tubing —1— is internally threaded for the reception of an externally threaded portion of a valve casing —2—. The casing —2— has a reduced end or projecting portion —3— also externally threaded and extending in the tubing —1— and provided with an internally extending conical seat adapted to receive a frusto-conical head or jamb —4— on the end of a feed pipe —5—. This feed pipe extends through the tubing —1— and is operably connected to a source of liquid supply under pressure, not necessary herein to illustrate or further describe.

The jamb —4— is held in engagement with its seat by means of an internally threaded jamb nut —6—, operating upon the threaded end —3— of the casing —2—. The jamb nut —6— is preferably, as shown, of substantially the same external diameter as the internal diameter of the drop tubing —1—.

The casing —2— is provided with a zig-zag conduit —7— leading from the conical seat in the end —3— to a secondary gas reservoir formed of a hollow section —8— having an externally threaded end fitted into and operably connected to an internally threaded portion of the casing —2—. The channel —7— is so arranged as to form a valve seat —9—, in connection with which a sliding valve —10— operates to cut off or to allow the passage of the fuel supply. For the purpose of supporting and operating this valve, the casing —2— is provided with a laterally projecting hollow portion —11—, adapted to receive a threaded valve stem —12— whereby the valve is operated by simply turning the valve stem. The outer portion of the projection —11— is externally threaded for receiving the usual packing nut —13— to prevent leakage.

The section —8— is provided with a laterally projecting arm —14— preferably as shown, substantially right angular in cross section and having a conduit —15— leading therethrough and communicating with the reservoir formed in the main body of

the section —8—. The lower end of the arm —14— is externally threaded and provided with an internally extending conical seat adapted to receive a frusto-conical jamb —16— preferably formed integral with a removable vaporizer —17—, the jamb held in liquid-tight connection with its seat by means of an internally threaded jamb nut —18—.

10 The lower end of the section or reservoir —8— is externally threaded and adapted to coact with and be received by an internally threaded portion of a projection —19— upon a hollow inverted J-shaped mixing chamber —20—, preferably formed of a single casting and having a burner head —21— secured to its shorter end in any suitable and well known manner, not necessary herein to describe. The burner head —21— is provided with a mantle —22— attached thereto and adapted to be heated by the burning fuel to an incandescent heat.

15 The section —8— is adapted to receive and support a shade-holder —23— of circular or other form, positioned above the arm —14— so as to inclose the same. A shade —24— is secured thereto by means of adjustable screws —25— passing through the flanged portion —26— of the shade-holder. The shade-holder is further provided with a canopy or cover —27— having air passages —28— therethrough, affording an outlet or ventilation for the lamp chamber.

20 The vaporizer —17— above referred to extends downwardly from its point of connection to the arm —14— in a direction substantially parallel with the section —8— and is curved around the horizontal portion of the mixing chamber so as to lie between the longer arm of the mixing chamber and the mantle —22— and is flattened toward its lower end, and bent laterally at substantially a right angle to itself across the open lower end of the longer arm of the mixing chamber —20— and is provided with an orifice or outlet —29— discharging upwardly into the mixing chamber. It will be readily apparent that when the lamp is once in operation, the adjacent portion of the vaporizing tube is directly subjected to radiation from the incandescent mantle, whereby the vaporization of the liquid fuel is automatic and continuous.

25 The lower side of the flange upon the vaporizer is provided with an opening registering with the orifice or outlet upon the upper side thereof and this opening is surrounded with a suitable internally threaded circumferential flange or embossment —30— forming communicating means for the insertion of a needle, or other clean-cut device for the discharge orifice —29—. The flange —30— is normally provided with a closing plug or screw —31—.

30 For the purpose of aiding in supporting

the vaporizer and for holding it in operable position relative to the burner and the mixing chamber, the longer arm of the mixing chamber is provided with a projecting flange —32— having a laterally extending opening 70 or conduit —33— adapted to receive a laterally extending projection —34— upon the end of the vaporizing tube, said projection formed by cutting away a portion of said tube.

35 The vaporizing tube —17— is provided with a wick or packing —35— of asbestos or other material which acts as a filter for removing any foreign particles from the fluid. The lower end of this tube, just beyond the discharge orifice —29—, is flattened sufficiently to entirely close the passage therethrough and prevent the escape of fuel.

40 In operation, the liquid fuel under pressure passes from a tank, not shown, through the feed pipe —5— to the valve —10— and the supply may be regulated or shut off by means of this valve. The fluid then passes into the reservoir formed by the hollow section —8—, is forced into the vaporizing tube —17— and is filtered and retarded in its passage therethrough by the wick or packing —35—. By lighting a match or taper and applying the flame to the lower end of the tube —17—, the liquid fuel is vaporized and passes through the discharge orifice —29— into the mixing chamber —20—, is mingled with air and supplied to the mantle —22—. After the operation is once started, the radiation from the mantle sufficiently heats the tube —17— to vaporize the fuel so that the continuing operation is automatic.

45 What we claim is:

1. A lamp comprising a tubular mixing chamber having substantially parallel extending arms vertically arranged and a substantially horizontal connecting portion, a burner connected to one of said arms, a vaporizing tube discharging into the other arm of the mixing chamber and having a portion lying between the arms of the mixing chamber, said vaporizing tube extending in substantially a vertical direction and curved partly around the horizontal portion 115 of the mixing chamber and having its upper end operably connected to a source of fuel supply, and a valve in the connection between the vaporizing tube and its source of fuel supply.

50 2. A lamp comprising an inverted J-shaped mixing chamber, a burner connected to the shorter arm of said chamber, a vaporizing tube discharging into the longer arm and having a portion lying between 125 said burner and said longer arm, said vaporizing tube extending in substantially a vertical direction and having a curved intermediate portion partially encircling the horizontal portion of the mixing chamber, 130

the upper end of said tube operably connected to a source of liquid fuel supply and a valve in the connection between said vaporizing tube and its source of fuel supply.

3. A lamp comprising a hollow mixing chamber having substantially parallel extending arms, a burner connected to one of said arms, a vaporizing tube operably connected to a source of fuel supply and having a portion lying between the arms of the mixing chamber, the bottom of said tube bent at substantially right angles to the main body thereof and having a portion thereof cut away to form a notch and a laterally extending flange, a seat formed in a wall of the mixing chamber coöperating with said notch and flange to prevent movement of said tube in a direction toward or from the burner.
- 10 4. In a gas lamp, a reservoir section oper-

ably connected to a source of fuel supply, said reservoir section supporting a mixing chamber having vertically extending arms of unequal length and a substantially horizontal connecting portion, a vaporizing tube having one end operably connected to and supported by an arm extending from the reservoir section, said vaporizing tube having a portion partially encircling the horizontal portion of the mixing chamber and extending downwardly between the arms of the mixing chamber and having a port discharging into the longer arm thereof, and a mantle operably supported on the other arm.

In witness whereof we have hereunto set our hands this tenth day of June 1913.

LEO J. KAHLO.
ROY B. CAMERON.
